TUNGSTEN WIRE REDUCING MACHINE

Henry V. Schlacks, Berwyn, Ill., assignor to Western Electric Company, Incorporated, New York, N. Y., a corporation of New York

Application June 15, 1931, Serial No. 544,511

16 Claims. (Cl. 176—4)

This invention relates to a material treating apparatus and more particularly to an apparatus for reducing tungsten wire such as the wire used in making lamp filaments.

An object of this invention is to provide a simple and effective apparatus for reducing and testing tungsten wire.

In accordance with one embodiment of the invention, tungsten wire is passed through a bath which, by chemical action, reduces the diameter of the wire. The amount of reduction and the uniformity of diameter of the resultant wire are preferably controlled by controlling the length of wire immersed in the fluid while maintaining the speed of the wire substantially constant. The mechanism for varying the length of the immersed wire is preferably controlled in response to the electrical resistance of the treated wire in order to maintain the cross-sectional area and the resistance substantially uniform for a given setting of the apparatus.

Other objects of the invention will be apparent from the following description taken in connection with the accompanying drawings, wherein

Fig. 1 is a front elevational view of the apparatus;

Fig. 2 is an enlarged fragmentary view of the actuating mechanism;

Fig. 3 is a top plan view of the mechanism shown in Fig. 2;

Fig. 4 is a vertical sectional view taken along the line 4—4 of Fig. 2;

Fig. 5 is an enlarged sectional view taken along the line 5—5 of Fig. 1;

Fig. 6 is a sectional view taken substantially along the line 6—6 of Fig. 5;

Fig. 7 is an enlarged sectional view taken along the line 7—7 of Fig. 1, and

Fig. 8 is a wiring diagram illustrating the invention.

Referring now to the drawings wherein like reference numerals designate similar parts throughout the several views, numeral 10 designates a suitable support such as a bench upon which is mounted a pivotal support 11 for a supply reel 12 having tungsten filament wire 13 wound thereupon. A wire 13, when taken from the reel 12, is threaded around a series of sheaves 15 and 16 rotatably mounted upon an elevator 17 the lower end of which is arranged to extend into a treating tank 18. A treating bath is disposed in the treating tank 18 and consists of a suitable solution which is heated to a desired temperature by a heating unit 19 for reducing

the wire 13, as it is drawn therethrough, over the sheave 16. The upper end of the elevator 17 is carried by a movable bracket 19 slidably mounted upon guide rods 20, which are supported by a frame 21, and provided with an internally threaded portion 22 (Fig. 7) for receiving an adjusting screw 23. The adjusting screw 23 is rotatably carried by the frame 21 and is adapted to be manually rotated by the aid of a knurled head portion 24. Extending downwardly from the adjustable screw 23, and constituting a part of the adjusting means, is an adjusting shaft 25 having mounted upon the lower end thereof ratchets 26 and 27 connected together by a hub 28 which is fixed to the adjusting shaft. Positioned adjacent the ratchets 26 and 27 are pawls 29 and 30, respectively, operatively connected to electromagnetically actuated levers 31 and 32, respectively. The levers 31 and 32 are normally urged forwardly by springs 33 so as to normally position the pawls 29 and 30 free of the ratchets and are arranged to be moved rearwardly by the energization of electromagnets 34 and 35, respectively, when certain electrical circuits hereinafter described are closed.

After the wire 13 is passed over the sheaves 15 and 16 and through the treating bath it is passed through a rinsing bath 40 as shown in Fig. 1, there being provided a supply line 41 for continuously supplying a fluid to a rinsing tank 42 and a drain 43 extending into the rinsing tank for draining the excess fluid therefrom. After the wire leaves the rinsing tank 42 it is passed through a pair of mercury cups 45 and 46 which are positioned in a testing unit indicated generally at 47. The testing unit is composed of a thermostatic temperature control 48, a resistance testing unit including a galvanometer (not shown) and indicated generally at 49, and a heating unit 50. The heating unit 50 is controlled by the thermostatic temperature control 48 for maintaining a predetermined temperature, preferably a temperature of 90° F. within a casing 54 in which the mercury cups 45 and 46 are disposed. The casing 54 has hingedly fixed thereto a cover 55 provided with a transparent member 56 therein, enabling the operator to observe the wire 13 as it passes through the casing. The heat control unit 48 is operatively connected, in any suitable manner, to a thermostat 57 which is disposed adjacent a thermometer 58, the latter being visible through the transparent member 56.

The mechanism for advancing the wire 13 is shown in Figs. 1 to 4, inclusive, and consists of a

power shaft 60 operatively connected to a driven shaft 61 by a pinion 62 and a gear 63. The shaft 61 is journaled in a housing 64 and has a worm 65 mounted thereupon which interengages 5 a worm 66 of a spool rotating shaft 67. The shaft 67 is journaled in bearings disposed in the housing 64 and is provided with a longitudinally extending key 68 receivable in slots of spools 69 disposed upon the shaft 67. As shown in Fig. 2 10 a plurality of such spools may be disposed upon the shaft 67 and rest upon a collar 70, the spools being held against vertical displacement by a weight 71 which is removably disposed upon the shaft 67.

15 A cam shaft 75 is journaled in the housing 64 and is operatively connected to a worm 66 by a worm gear 76 mounted upon the shaft 75. At one side of the worm gear 76 is a distributor actuating cam 77 engaging a roller 78 of a lifting lever 20 79 for raising and lowering the lever. The lever 79 is pivoted at 80 and has its opposite end forked to receive a pin 81 of a reciprocating distributor bar 82. The bar 82 is journaled in bearings in the housing 64 and is normally urged downwardly 25 by a spring 83. Adjustably mounted upon the upper end of the reciprocating bar 82 is a distributor member 84 held in one of a plurality of fixed positions by a set screw 85 and adjusted relative to the reciprocating bar 82 by an adjusting nut 86. The strand 13 in passing from the testing unit 47 passes beneath a pin 87 of the distributor member 84 which guides the wire back 30 and forth over the adjacent spool 69 so as to evenly position the convolutions of the wire thereupon. 35

Upon the forward end of the cam shaft 75 are disposed switch actuating cams 90 and 91, the cam 90 being shown in Fig. 8 provided with a pair of raised cam portions 92 and the cam 91 40 shown in the same figure with a single raised portion 93 covering approximately one-fourth of the peripheral surface of the cam. The purposes of the cams 90 and 91 are to close switches 94 and 95, respectively, for closing circuits illustrated in 45 Fig. 8.

The circuits shown in Fig. 8 include a coil 100 for the electromagnet 34 and a coil 101 for the electromagnet 35. The coils 100 and 101 are disposed in circuits including contact blocks 102 and 50 103, respectively, spaced sufficiently from each other so that a galvanometer needle 104, when registering a zero reading, may be positioned therebetween without contacting with either end of the blocks. An actuating bar 105 is alternately 55 moved toward and away from the contact blocks 102 and 103 due to the energization of a solenoid 106, the latter being energized when the raised portion 93 of the cam 91 is moved to close a switch 107. The cam 91 is rotated at any desired speed, 60 such as ten revolutions per minute, to energize the solenoid at desired intervals and retain the solenoid in the energized condition until the cam 90 has closed and opened a switch 108 one or more times depending upon the number of raised 65 portions 92 upon the cam 90. Therefore, if the needle 104 of the galvanometer is positioned to the left, so that it will be between the contact block 102 and the actuating bar 105, a circuit will be completed, when the solenoid 106 is energized, to permit electrical energy to pass through the coil 101 of the electromagnet 35 and actuate a pawl 30 so as to lower the elevator 17. This 70 operation will be more thoroughly described hereinafter.

75 The galvanometer, which the needle 104 is a

part of, is controlled by a wheatstone bridge circuit 110 and as the portion of the wire 13 between the mercury cups 45 and 46 constitutes one arm of the bridge circuit, any variation in the resistance of the wire between the mercury cups will affect the position of the needle 104. When the apparatus is in operation and the wire, which passes through the mercury cups 45 and 46, is being wound upon one of the spools 69 a circuit is completed from a battery 111, through a relay 112, the mercury cup 46, the wire 13, the spool 69 upon which the wire is being wound, through the spool shaft 67 which is grounded to a base plate 113, and back to the battery. As the current flows through the relay 112 a switch 114 is closed completing a circuit which includes another relay 115, the energization of which opens a switch 116 in an alarm circuit 117 and closes a switch 118 in a circuit including the switch 107 and the solenoid 106.

From the foregoing description of the various parts of the apparatus the operation thereof may be more clearly understood. As the wire 13 is threaded around the sheaves 15 and 16 of the elevator mechanism, through the rinsing bath 40, the mercury contact cups 45 and 46, beneath the pin 87 of the distributor 84 and secured to one of the spools 69, a motor, or any suitable power means (not shown), is energized for rotating the power shaft 60, thus imparting a rotary movement to the spool shaft 67 and to the cam shaft 75. Let it be assumed that the treating bath in the treating tank 18 is heated by means of a heating unit 19 to the desired temperature and that the temperature within the casing 54 is approximately 90° F. The treating bath is composed of a suitable solution, such as equal portions of sodium nitrate and sodium nitrite solution, which is maintained at a constant predetermined temperature, preferably at a temperature of 700° F. As the wire 13 passes into the treating bath around the sheave 16 and out of the treating bath a chemical reaction occurs and the wire is reduced in size. The reduction in the wire may be varied by varying the time in which the wire remains in the treating bath. This variation in the time in which the wire remains in the treating bath is brought about by the actuation of the galvanometer needle 104, this needle being moved to register the resistance of the wire 13 between the mercury contact cups 45 and 46. If the resistance of the portion of the wire 13 between the mercury cups 45 and 46 is high the needle 104 will be moved to the left (Fig. 8) and while in this position the actuating bar 105 will move it into engagement with the contact block 102, due to the energization of the solenoid 106 when the switch 107 is closed by movement of the cam 93, and move the contact block 102 into engagement with an adjacent contact point to close one point of the circuit including the electromagnet 35. Immediately upon the energizing of the solenoid 106 the switch 108 will be closed and opened one or more times, depending upon the number of raised portions 92 on the cam 90, so as to energize the electromagnet 34, causing a rearward movement of the lever 31, which moves the pawl 29 into operative engagement with the ratchet 27 to rotate the ratchet with the adjusting shaft 25 a predetermined distance. The electromagnet 34 may be energized any desired number of times during each energization of the solenoid 106 by providing the desired number of raised portions 92 upon the cam 90. In

the present instance the electromagnet 34 is energized twice during each energization of the solenoid 106 and during the energization of the electromagnet 34 rotative movement is imparted 5 to the adjusted screw 23 to move the elevator 17 upwardly thus making shorter the period of time in which the wire 13 remains in the treating solution. If the resistance of the wire 13 is still too high the needle 104 will remain in a position 10 to the left (Fig. 8) and during the next revolution of the cam 91 the solenoid 106 will again be energized to close the circuit through the electromagnet 34 the coil 101, which is a part thereof, thus rotating the adjusting screw 23 to raise the 15 elevator 17 a predetermined distance. A similar operation will take place when the resistance of the wire 13 between the mercury cups 45 and 46 is too low. In this operation the needle 104 in registering the resistance of the wire will be 20 moved to the right (Fig. 8) and when the solenoid 106 is energized a circuit will be closed through the coil 100, which is a part of the electromagnet 35, and during the energization of the electromagnet 35 the lever 32 will be actuated 25 to move the pawl 30 into operative engagement with the ratchet 26 thus rotating the ratchet with the adjusting shaft in a counterclockwise direction (Fig. 5) to lower the elevator.

During the operation of the apparatus a switch 30 120 of the alarm circuit is closed so that when the switch 116 is released, due to the de-energization of the relay 115, the alarm circuit 117 will be closed to energize any suitable alarming device. The purpose of the alarm circuit is to notify the 35 operator when the wire 13 becomes broken. The relay 112 is electrically connected to the spool 69 upon which the wire is wound and when the wire becomes broken the circuit including the relay 112 will be opened, which will open the switch 40 114, and de-energize the relay 115, permitting the switch 116 to be moved so as to close the alarm circuit and permit the switch 118 to open, thus rendering the circuit including the solenoid 106 ineffective. If the wire 13 should break during 45 the operation of the apparatus the elevator 17 may be moved upwardly, to remove the wire from the treating bath without varying the position of the movable bracket 19, and held in any desired upward position by a retaining member 50 121 resting upon a downwardly tapered surface of the bracket 19 and receivable in any of a plurality of notches 122 of the elevator. While the elevator is in the upward position the wire may be rethreaded through the apparatus, an 55 end thereof secured to one of the spools 69 and the elevator then lowered into the proper position in the treating bath.

An important feature of this invention is the provision of means for testing the electrical characteristics of tungsten wire at predetermined intervals during the advancing thereof through a treating solution and actuating mechanism, resultant of the test, for varying the immersion depth of the wire in the treating solution.

Another important feature is the provision of 65 means whereby the elevator may be moved upwardly to move the wire out of the treating solution without actuating the adjusting screw, thus making it possible to rethread the wire through the apparatus, start the advancing means and lower the elevator to position the wire within the treating solution at the immersion depth previously occupied thereby.

Although a specific form of the invention has

been described herein the invention is to be limited only by the scope of the appended claims.

What is claimed is:

1. In a material treating apparatus, a treating bath, means for advancing strand material 5 through said treating bath, means for measuring a factor related to the cross-section of the strand material, and means responsive to said measuring means for varying the time in which the strand remains in said treating bath in accordance with 10 the cross-section of the strand.

2. In a material treating apparatus, a treating bath for reducing the cross-sectional area of a strand and varying the electrical resistance thereof, means for measuring the resistance of 15 a portion of the strand, means for advancing the strand through said treating bath, and means responsive to said resistance measuring means for varying the length of time in which the strand remains in said treating bath in accordance with 20 the resistance of the strand.

3. In a material treating apparatus, means for advancing a strand, a treating tank, a treating solution disposed in said tank for varying the size of the strand, and means for raising or lowering 25 the strand in said treating bath during the advancing of said strand for varying the time in which said strand is subjected to said treating bath.

4. In a material treating apparatus, a treat- 30 ing bath, means for advancing material, means for directing the material into and out of said treating bath, means for testing the electrical characteristics of the material after passing through said treating bath, and means for vary- 35 ing the position of said directing means in response to said electrical characteristics for varying the time in which the material is subjected to said treating bath.

5. In a material treating apparatus, means for 40 advancing strand material through a treating solution for varying the cross-sectional area thereof, means for testing the electrical characteristics of the strand material after passing through said treating solution, and means asso- 45 ciated with and responsive to said testing means for varying the time in which the material is immersed in the treating bath.

6. In a material treating apparatus, means for 50 reducing the cross-sectional area of material, means for electrically testing the material including a bridge circuit, a portion of the material which has been reduced constituting one arm of said bridge circuit and means associated with the testing means for maintaining said cross- 55 sectional area uniform.

7. In a material treating apparatus, means for 60 reducing the cross-sectional area of material, means for electrically testing the material including a bridge circuit, a portion of the material which has been reduced constituting one arm of said bridge circuit, and means associated with and responsive to said testing means for varying the cross-sectional reduction of a material.

8. In a material treating apparatus, a treat- 65 ing bath, means for advancing material, an ele- 70 vator mechanism arranged to direct the material, while advancing, into and out of said treat- 75 ing bath, means for testing the electrical characteristics of the material passing from said bath, and means associated with said testing means for varying the position of said elevating means relative to said bath.

9. In a material treating apparatus, a treat- 75 ing bath, means for advancing material, an ele-

- vator mechanism arranged to direct the material, while advancing, into and out of said treating bath, means for testing the electrical characteristics of the material passing from said bath,
- 5 means associated with said testing means for varying the position of said elevating means relative to said bath, and means for rendering said last named means ineffective if the material being advanced should break.
- 10 10. In a material treating apparatus, a treating bath, means for advancing material, an elevator mechanism arranged to direct the material, while advancing, into and out of said treating bath, means for testing the electrical characteristics of the material passing from said bath, means associated with said testing means for varying the position of said elevating means relative to said bath, means for rendering said last named means ineffective if the material being advanced should break, and indicating means arranged to be energized upon the breaking of said material.
11. In a material treating apparatus, means for reducing the cross-sectional area of material
- 25 while being advanced, means for advancing the material, means for testing the electrical characteristics of the material, means associated with said testing means for varying the cross-sectional reduction of said material, and means for alternately energizing and de-energizing said last named means during the advancing of said material.
12. In a material treating apparatus, means for reducing the cross-section of the material, and
- 35 means for varying the amount of said reduction including a bridge circuit having a portion of the material in one arm thereof, a galvanometer having a pointer, and means responsive to the position of the pointer for effecting said variation.
- 40 13. In an apparatus for treating tungsten wire, a treating bath for reducing the cross-section of the wire, means for advancing the wire through

the bath at a constant rate, and means varying the period of time the wire is in the bath to obtain a selected varying reduction.

14. In an apparatus for treating tungsten wire, a treating bath, means for advancing the wire through said bath at a predetermined rate, means for varying the length of wire immersed in said bath, means responsive to the variation of the electrical characteristics of the wire, and means actuated by said responsive means for controlling the means for varying the length of wire immersed in the bath.

15. In an apparatus for treating wire, a treating bath, means for advancing the wire through said bath at a predetermined rate, driven means for varying the length of wire immersed in said bath, a control apparatus for said driven means comprising a bridge circuit, a variable impedance element in said circuit, a galvanometer having a movable element, a pair of switches, a reciprocable means cooperating with the movable element to actuate the switches according to the position of the movable element, and means for driving said driven means in one direction or the other depending upon which switch is actuated.

16. In an apparatus for treating wire, a treating bath, means for advancing the wire through said bath at a predetermined rate, means for varying the length of wire immersed in the bath, means responsive to the variation of the electrical characteristics of the wire comprising a galvanometer having a movable element, a pair of electrical contact members, a reciprocable member cooperating with said movable element to actuate the contact members, a rotatable shaft, and means for rotating said shaft in either direction in accordance with the contact member actuated, said shaft actuating the means for varying the length of wire immersed in the bath.

HENRY V. SCHLACKS.
